PLATE AND CUP SUPPORTING DEVICE

Harold J. Le Vesconte, Glendale, Calif.

Application October 25, 1946, Serial No. 705,631

10 Claims. (Cl. 248—156)

1

This invention relates to a cup and plate support useful in picnics or in camping in that the plate and cup or other beverage container are supported at a level convenient to a person seated on the ground. As is well known it is difficult to eat from a plate held in the lap or placed on the ground and it is likewise difficult on such occasions to find a place which is sufficiently level to support a cup or other beverage container in a level position. Additionally, under such conditions sand, dirt or insects are apt to get into the food all of which to many people provides a powerful deterrent to what would otherwise be an enjoyable occasion.

To overcome these objections it is an object of the present invention to provide a support for a plate and cup or other beverage container in the form of a collapsible assembly which when assembled may be inserted in the ground and when so placed will position the plate and beverage at a distance above the ground which with relation to a person seated on the ground is comparable in height to the level of a table when a person is seated on a chair.

Another object of the invention is to provide a plate and cup supporting means which is so constructed and arranged that when in use the plate supporting stake will be prevented from turning.

Still another object of the invention is to provide a plate support in which the means for attaching it to the ground comprises a stake of small diameter which may therefore be inserted in the ground with relative ease.

A still further object of the invention is to provide a device of the above character in which the supporting means is collapsible thereby making it possible to pack the disassembled apparatus in a relatively small container.

A still further object of the invention is to so construct the attaching means for the plate and the holder for a cup or other beverage container that they interlock to rigidly maintain the parts in assembly.

Still another object of the invention is to provide a device of the above described character composed of few parts all of which are simple in design and which therefore contribute to economy in manufacture, and to reliability and convenience in use.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

2

Fig. 1 is a top plan view slightly in perspective of the device assembled and positioned for use.

Fig. 2 is a side elevation of the device assembled and positioned for use.

Fig. 3 is a side elevation of the supporting means collapsed for packing.

Figs. 4 and 5 are fragmentary sectional views taken on the lines 4—4 and 5—5 respectively of Fig. 2.

Fig. 6 is an end elevation of the holding means for a cup or other beverage container, and

Fig. 7 is a top plan view of the device assembled for use, certain of the concealed parts being shown in dotted lines.

In the form of execution of the invention shown in the drawings the device comprises a plate 1 having on the underside thereof, a socket in the form of a loop 2 of metal fixed thereto by any suitable means such as soldering, brazing or welding. The loop 2 is relatively wide and shallow and accommodates the shanks 3 and 4 of the rebent end 5 of a stake element 6. The stake element is formed of wire having considerable spring and the free end 1 of the shank 3 is bent downwardly to provide a grip so that in assembly the shanks 3 and 4 may be sprung toward each other to permit easy insertion of the bend 5 into the loop 2 and upon release the shanks 3 and 4 will tend to separate and tightly engage the opposite sides of the loop 2. It will be noted that the loop 2 is of somewhat heavier metal than the plate and that since the end portions of the loop extend between the shanks 3 and 4 of the rebent or loop end 5 of the stake element and the plate it is possible to use a plate element of light gauge metal since the reaction between the stake and loop 2 is entirely absorbed by the loop.

The stake assembly, in addition to the element 6, includes a second element 8 which at its upper end is formed with a spiral 9 frictionally engaging the element 6 and terminating in a hand piece portion 10 by which it may be grasped to force it into the ground. The element 6 near its lower end is provided with a spiral portion 11 which surrounds and frictionally engages the element 8 and which thence extends laterally a short distance as at 12 and terminates in a short pointed portion 13 offset from the pointed portion 14 of the element 8.

The holder for a cup or other beverage container comprises a frame portion formed of a relatively heavy U-shaped wire 15 the outer ends 16 and 17 of which are curved outwardly away from and thence toward each other to define a substantially circular outline. The rebent end portion 18 is of slightly greater width than the inside

dimension of the rebent portion 5 of the stake element 6. Preferably it is formed of the same size and type of wire as is employed for the stake elements. In assembly, the shank portions 19 and 19' are grasped and sprung toward each other and the rebent end is inserted within the loop 2 inside of the shanks of the loop of the stake element. Upon release, the shanks 18 and 19 will tend to spring apart thus aiding the shanks of the stake element loop in tightly engaging the side walls of the loop 2, the general arrangement being best shown in Fig. 5.

As shown in Figs. 1, 2 and 7, the shanks 19 and 19' are of sufficient length to position the curved portions 16 and 17 slightly beyond the edge of the plate 1. Fixed to the shanks 18 and 19 at 20 and 21 respectively are ends of U-shaped wires 22 and 23 which extend downwardly and thence laterally toward the free ends of the cup holder and thence upwardly to said ends to which they are affixed with consequent formation of a vertical slot 25 through which the handle of a cup resting on the lateral portions of the wires 23 and 24 may project. Additionally, the cupholder is provided with a second series of U-shaped wires 26, 27 and 28 the lateral portions of which extend transversely to the wires 23 and 24 and which are interlaced therewith to form a bottom in the cupholder and to tie the free ends thereof together.

To put the device into use the plate and stake elements are first assembled, then the cupholding element is attached to the assembled plate and stake after which the collapsed stake assembly is pressed into the ground until the lateral portion 12 of the stake element 6 comes into contact therewith. Then by grasping the hand piece 10 the stake element 8 is forced downwardly into the ground with the straight portions of the stake element 6 acting as a guide for the upper end of the element 8.

Since the spirals 9 and 11 frictionally grip the wires and since the plate and cupholder are fixed to the stake element the whole assembly is sufficiently rigidly attached to the ground to provide a satisfactory surface from which a person seated on the ground may eat. It may be noted further that when thus installed, the weakest point in resistance to bending if only a single stake element were used would be the point at the surface of the ground and that by the improved construction here disclosed, that point is substantially reinforced by the inter-engagement of the spiral portions of the wires with incident raising of the point of bending closer to the plate where it offers substantially more resistance.

Still further since the plate and cupholder are attached to the stake element 6 which is provided with an offset ground-engaging portion there will be no tendency of the assembly to turn about the axis of the stake element 8. Also due to the formation of the various parts a set of plates, stake assemblies and cupholders may be packed in a container of small size when not in use.

Still another advantage lies in the fact that a device of this character makes it unnecessary for the selection of a level spot of ground for picnic lunches since the plates will be held level regardless of the slope of the ground and thus areas heretofore undesirable because of the slope of the ground are made available for picnics.

While the preferred size is that herein specifically disclosed, it will be appreciated that without departure from the invention, a somewhat longer and stiffer stake assembly may be

provided which will bring the plate and cupholder to a level convenient for a person seated on a chair or the like.

Also, while the interengagement between the stake elements is here shown in the form of spirals formed integrally in the elements it will be appreciated that formations other than spirals may be employed or that the stake elements may each be supplied with sleeves through which the other element may slide with the same advantages as is achieved by the disclosed construction.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. In a positioning and holding apparatus for a cup and plate, a plate having a socket, a stake having one end adapted to be inserted in the ground and the other end adapted to engage said socket, and a holding means for a cup or the like also engageable with said socket, said stake comprising a pair of wires each of which has a ground engaging end and a spiral portion surrounding the other wire, one of said wires having a loop at one end engageable with said socket.

2. In a positioning and holding apparatus for a cup and plate, a plate having a socket, a stake having one end adapted to be inserted in the ground and the other end adapted to engage said socket, and a holding means for a cup or the like also engageable with said socket, said stake comprising a pair of wires each of which has a ground engaging end and a spiral portion surrounding the other wire, one of said wires having a loop at one end engageable with said socket, said cupholder having a shank adapted to engage said socket within the confines of said loop.

3. In a positioning and holding apparatus for a cup and plate, a plate having a socket, a stake having one end adapted to be inserted in the ground and the other end adapted to engage said socket, and a holding means for a cup or the like also engageable with said socket, said stake comprising a pair of wires each of which has a ground engaging end and a spiral portion surrounding and slidably on the other wire, one of said wires having a loop at one end engageable with said socket, said cupholder having a shank adapted to engage said socket within the confines of said loop, said loop being disposed in a plane normal to the axis of said stake and being normally of slightly greater width than said socket and having capacity to be momentarily decreased in width for insertion in said socket and thereafter to frictionally grip the sidewalls of said socket.

4. In a positioning and holding apparatus for a cup and plate, a plate having a socket, a stake having one end adapted to be inserted in the ground and the other end adapted to engage said socket, and a holding means for a cup or the like also engageable with said socket, said stake comprising a pair of wires each of which has a ground engaging end and a spiral portion surrounding the other wire, one of said wires having a loop at one end engageable with said socket, said cupholder having a shank adapted to engage said socket within the confines of said loop, said cupholder shank comprising a U-shaped wire adapted to be compressed for inser-

tion into said socket and said loop on said stake and upon release to expand and frictionally engage said loop and increase the frictional engagement between said loop and said socket.

5. In a positioning and holding apparatus for a cup and plate, a plate having a socket, a stake having one end adapted to be inserted in the ground and the other end adapted to engage said socket, and a holding means for a cup or the like also engageable with said socket, said stake comprising a pair of wires each of which has a ground engaging end and a spiral portion surrounding the other wire, said cupholder having a shank adapted to engage said socket within the confines of said loop, said loop being disposed in a plane normal to the axis of said stake and being normally of slightly greater width than said socket and having capacity to be momentarily decreased in width for insertion in said socket and thereafter to frictionally grip the sidewalls of said socket, said cupholder shank comprising a U-shaped wire adapted to be compressed for insertion into said socket and said loop on said stake and upon release to expand and frictionally engage said loop and increase the frictional engagement between said loop and said socket.

6. In a positioning and holding apparatus for a cup and plate, a plate, a strap of metal secured to the underside of said plate and constructed and arranged to form a relatively wide, shallow socket, a stake having one end adapted to be inserted in the ground and the other end adapted to engage said socket and a holding means for a cup or the like also engageable with said socket, said stake comprising a pair of wires each of which has a ground engaging end and a spiral portion surrounding the other wire, one of said wires having a loop at one end engageable with said socket.

7. In a positioning and holding apparatus for a cup and plate, a plate having a socket, a plate-supporting stake having one end adapted to be inserted in the ground and the other end adapted to engage said socket, and a holding means for a cup or the like also engageable with said socket, said cupholder having a shank extending from said socket to a point beyond the periphery of said plate and said cupholder at its free end having a slot arranged to provide clearance for the handle of a cup positioned in said holder.

8. In a positioning and holding apparatus for a cup and plate, a plate, a strap of metal secured to the underside of said plate and constructed and arranged to form a relatively wide, shallow socket, a plate-supporting stake having one end adapted to be inserted in the ground and the

other end adapted to engage said socket and a holding means for a cup or the like also engageable with said socket, said stake comprising a pair of wires each of which has a ground engaging end and a spiral portion surrounding the other wire, said cupholder having a shank extending from said socket to a point beyond the periphery of said plate and said cupholder at its free end having a slot arranged to provide clearance for the handle of a cup positioned in said holder.

9. In a device of the character described, the combination of a plate and a stake means, said stake means comprising a pair of relatively slideable interengaging elements each of which at one end is adapted to be forced into the ground and one of which at its other end is adapted to have interlocking means engageable with said plate, said other element at its other end having means constructed and arranged to facilitate its being pressed into the ground to a greater extent than said plate engaging element, said sliding engagement between said elements operating to guide said last named element in its further penetration of the ground.

10. In a device of the character described, the combination of a plate and a stake means, said stake means comprising a pair of relatively slideable interengaging elements each of which at one end is adapted to be forced into the ground and one of which at its other end is adapted to have detachable interlocking means engageable with said plate, said plate engaging element having its ground engaging end offset laterally from said other element thereby becoming effective when both elements are inserted in the ground to resist any turning tendency of said plate, said other element at its other end having means constructed and arranged to facilitate its being pressed into the ground to a greater extent than said plate engaging element.
